DUAL SUPPORT BRACKET FOR TRASH CANS

Tacko D. Alissandratos, P.O. Box 606,
Tampa Springs, Fla. 33589

Filed Apr. 10, 1970, Ser. No. 22,374

Term of patent 14 years

Int. Cl. D8—08

U.S. Cl. D8—234

FIG. 1

FIG. 2

FIG. 3

FIG. 4

FIG. 5

In the drawing:

FIG. 1 is a top perspective view of a dual support bracket for trash cans showing my new design;

FIG. 2 is a top plan view;

FIG. 3 is an end elevational view;

FIG. 4 is a side elevational view; and

FIG. 5 is a bottom plan view thereof.

I claim:

The ornamental design for a dual support bracket for trash cans, as shown.
